CLAIM

(22) Filed: **Dec. 3, 1999**

We claim the ornamental design for a shipping container with slide valve, as shown and described.

(51) LOC (7) Cl. **03-01**

DESCRIPTION

(52) U.S. Cl. **D3/273; D3/272**

FIG. 1 is a top plan view of a shipping container with slide valve, showing my new design, wherein the bottom plan view is identical;

(58) Field of Search D3/272, 273; 229/109, 229/108, 110; 220/441, 408, 410; 222/561

FIG. 2 is a front elevational view thereof, wherein the slide valve is in a closed position;

(56) **References Cited**

FIG. 3 is a front elevational view thereof, wherein the slide valve is in an open position;

U.S. PATENT DOCUMENTS

FIG. 4 is a right side elevational view thereof, wherein the left side elevational view is a mirror image;
